Primary Examiner — Jack Reickel*Assistant Examiner* — Sydney M Evans(74) *Attorney, Agent, or Firm* — QuickPatents; Kevin Prince(57) **CLAIM**

The ornamental design for a threaded adapter, as shown and described.

DESCRIPTION

FIG. 1 is a top perspective view of a threaded adapter, showing my new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a left-side elevational view thereof, the right-side elevational view being a mirror image thereof.
